UNITED STATES PATENT OFFICE.

WILLIAM THORNE ERICKSON, OF NEW YORK, N. Y.

STAMP AND LABEL

1,003,443.

Specification of Letters Patent. Patented Sept. 19, 1911.

Application filed August 17, 1910. Serial No. 577,660.

To all whom it may concern:

Be it known that I, WILLIAM THORNE ERICKSON, a citizen of the United States, and resident of New York, in the county of 5 New York and State of New York, have invented certain new and useful Improvements in Stamps and Labels, of which the following is a specification.

My invention relates to stamps, labels and 10 the like, with particular reference to that class of such articles which are applied to receiving surfaces by adhesion; my object being to produce a stamp or label which shall be proof against second using.

15 Governments the world over experience great losses in revenue owing to the fact that stamps, especially those of high denomination are used by dishonest persons several times over, it being an easy matter 20 to remove the ordinary revenue (or postage) stamp from the package or document to which it has been applied by steaming or soaking, and then by chemical washings or other means removing all traces of cancellation that may appear on the recovered 25 stamp. Similarly, private business concerns and individuals are defrauded and the public deceived by the same practices on labels and other identifying marks.

30 My invention aims to produce an adhesive stamp or label having characteristics which will effectually prevent its removal in complete or usable condition from any surface to which it has once been applied.

35 The invention consists of a sheet of transparent material to which suitable pigments, which constitute the design or other matter of the stamp or label, are applied partly in permanent relation with said transparent 40 sheet and partly in removable or transferable relation therewith, and are arranged thereon in separate and distinct films, but in such manner that they mutually contribute to produce a complete, unitary and 45 intelligible whole visible in entirety from one surface of said sheet; the said transparent sheet being adapted to be adhesively applied to a receiving surface and thereafter removed therefrom if desired, whereby

50 the pigments permanently affixed to the sheet will be withdrawn leaving an incomplete design in pigment only on said receiving surface. Obviously the remaining pigment can not be removed without de- 55 struction.

In the accompanying drawing Figure 1 is an elevation showing my improved stamp or label applied to a receiving surface; Fig. 2 is a similar view showing the transparent sheet partly removed; Fig. 3 is a view showing the design on the receiving surface after the sheet has been removed; Fig. 4 is a view of the removed sheet; Figs. 5 and 6 are exaggerated sectional views of the stamp or label; and Fig. 7 is a similar view showing 60 an alternative form.

Referring to the drawings by numerals, in which similar characters denote similar parts throughout the several figures, 1 represents a body of transparent paper, parchment or other suitable thin and preferably flexible material, hereinafter referred to as the "sheet".

2 represents a film or coating of printers' ink, paint, or other pigment applied directly 75 upon the sheet 1, either on the under surface thereof as best indicated in Figs. 5 and 6, or on the upper surface as shown in Fig. 7. This film or coating constitutes an indispensable and component part of the design 80 of the stamp or label.

3 denotes a transparent and soluble sizing washed over the back or under surface of sheet 1 and covering the pigment 2 (Figs. 5 and 6). Laid over this transparent sizing 85 is a film or coating 4 of printers' ink, paint or other pigment which constitutes the complementary portion of the design represented in part by the film 2. The film 4, preferably does not extend across the area 90 occupied by the film 2, but is carefully matched to and arranged around said area so that the two films present an unbroken appearance as seen through the sheet from its upper or front surface.

95 5 denotes a coating of adhesive substance laid over pigment 4 and preferably over the entire back or under surface of sheet 1, whereby the stamp or label, as a whole, may be applied to a receiving surface 6.

100 A stamp or label such as described may be used precisely the same as an ordinary stamp—that is to say, pasted to a package or document and thereafter canceled by punchings or markings in the usual manner; or it may be canceled by removing the sheet 1 which, as will be understood from the foregoing description and the drawings, will carry away so much of the design as to 105 positively indicate cancellation. This effect 110

may be enhanced by arranging the pigments 2 in the form of any commonly accepted mark of cancellation, such as the cross shown in the drawings.

5 My invention does not contemplate means for preventing the removal of the sheet 1 from its receiving surface, inasmuch as such removal accomplishes the primary object of the invention, which is to prevent second use 10 of the stamp. If desired, however, such removal may be rendered difficult by the use of tenacious glues or slowly soluble substances on the back of the sheet. But it is preferred that the sheet be easy of removal 15 as in some systems of business it may be found of advantage to preserve the transparent sheets as a record of stamps used.

The particular nature of and manner of applying the pigments or the soluble or the 20 adhesive substances herein referred to forms no part of the present invention, and is therefore not described. Any of the several methods and materials used in the manufacture of the well known decalcomania or 25 transferable picture may be employed in carrying out my invention.

Having thus described my invention what I claim is:

1. A stamp or label of the character described comprising a transparent sheet, a film of pigment permanently applied thereto in definite arrangement and outline and forming a component part of a predetermined design, an insulating coating of soluble material applied to one side of said sheet, a second film of pigment applied to said soluble material and matched to and around the area occupied by said permanent film, the two films mutually contributing to 30 form a complete design, and a coating of adhesive material laid over said second film, whereby a design having a clearly defined
- 35
- 40

blank area may be caused to adhere to a receiving surface.

2. A stamp or label of the character described comprising a transparent sheet, a film of pigment permanently applied to one surface thereof in definite arrangement and outline and forming a component part of a predetermined design, an insulating coating 45 of soluble material applied to the opposite side of said sheet, a second film of pigment applied to said soluble material and matched to and around the area occupied by said permanent film, the two films mutually 50 contributing to form a complete design, and a coating of adhesive material laid over said second film, whereby a design having a clearly defined blank area may be caused to 55 adhere to a receiving surface.

3. A stamp or label of the character described comprising a transparent sheet, a primary film of pigment permanently applied thereto in definite arrangement and outline and forming a component part of a 60 predetermined design, a secondary removable film laid over the primary film and adapted to be transferred to a receiving surface, an insulating coating of soluble material interposed between said films, the two 65 films mutually contributing to form a complete design, and a coating of adhesive material laid over said second film, whereby a 70 design having a clearly defined blank area may be caused to adhere to a receiving surface.

Signed at New York N. Y. in the county of New York and State of New York this 13th day of August A. D. 1910.

WILLIAM THORNE ERICKSON.
